[57] CLAIM

The ornamental design for a frame support for a reclining chair, as shown and described.

DESCRIPTION

FIG. 1 is a side elevational view of a frame support for a reclining chair, showing the new design;

FIG. 2 is an end elevational view of the frame support for a reclining chair, the opposite end elevational view being a mirror image thereof;

FIG. 3 is a bottom plan view of the frame support for a reclining chair;

FIG. 4 is a top plan view of the frame support for a reclining chair;

FIG. 5 is an enlarged fragmentary perspective view of one end of the frame support for a reclining chair to more clearly illustrate the design thereof, the opposite end fragmentary perspective view being a mirror image thereof; and,

FIG. 6 is a further enlarged top plan view of a portion of one end of that shown in FIG. 4, the opposite end being a mirror image thereof.
